Filed May 13, 1960, Ser. No. 60,561

Term of patent 14 years

(Cl. D58—13)

Fig. 1

Fig. 1 is a front perspective view of a tool kit embodying our design.

Fig. 2 is a perspective view thereof, in open position.

The two lower compartments in the rear section of the article are substantially the same as the upper compartment shown.

The rear of the kit and the back side of the partition are substantially plain in configuration.

The portions stippled in the drawing contrast in color with the unstippled portions.

We claim:

The ornamental design for a tool kit, substantially as shown and described.
